UNITED STATES PATENT OFFICE.

HIPPOLYTE ROMANOFF, OF NEUILLY SUR SEINE, FRANCE.

CLOSING DEVICE FOR HAND BAGGAGE AND CASES AND THE LIKE.

Application filed November 2, 1926. Serial No. 145,848.

The present invention has for its subject a closing device for baggage and for cases or boxes of any kind carried by hand.

This device is more particularly characterized by: its automatic closure when the two parts of the case to be closed are brought together, which closure is obtained by the combination of a lever elastically pressed by a spring; the arrangement for opening the device, which device is opened by simply exerting a pressure upon one of the ends of the handle; the arrangement for keeping the case closed when it is carried, the closing device being locked in its closed position by the handle pulling on one of the ends of a pivoted lever carrying the bolt.

In the accompanying drawing:

Figure 1 shows in elevation a general arrangement of the closing device according to the invention.

Figure 2 is a plan view of this arrangement, the handle being assumed to be removed.

Figure 3 is an end view of the frame which carries the mechanism.

Figure 4 is a view in elevation of the lever carrying the bolt.

Figure 5 is a plan view of this lever.

Figure 6 is an end view of this lever and of the bolt which is integral with it.

Figure 7 shows in elevation the frame or strap for pivotally mounting the handle upon the frame.

Figure 8 is a plan view of the same part.

Figure 9 is a view in elevation of the guide plate mounted upon the part of the case which is not integral with the mechanism.

Figure 10 is an end view of this guide plate.

Figure 11 is a view in elevation of the stop plate mounted upon the part of the case which is not integral with the mechanism, upon which plate the bolt is stopped.

Figure 12 is an end view of this stop plate.

As shown in Figure 1, a frame 1, which is stamped out and is of suitable form, is attached by means of its angle plate 2 and its end pieces 3, upon one part of the case to be closed. This frame 1, of reversed U section, is pierced at one end with a long eye or slot 4 in which moves the pivot 5.

Upon the pin 5 is pivotally mounted, in the interior of the frame, on the one hand a bolt carrying lever 6 (Figs. 4, 5 and 6), and on the other hand the strap 7 (Figs. 7 and

8) the end of which is inserted into the handle 8.

The lever 6, pivoted at its centre upon its pin 9 secured to the frame, carries at its other end a bolt 10 (Fig. 6) adapted to be raised and lowered when the pin 5 is moved downwards and upwards in the slot 4.

At the other end of the frame 1 is formed a circular eye 11 in which is mounted a pin 12 upon which are pivoted, in the interior of the frame, on the one hand a spring 13 which is normally pressed upon the lever 6 and, on the other hand, the strap 7 the end of which is inserted in the handle 8.

When the case is closed the bolt 10 engages upon a latch plate 14 (Figs. 1, 11 and 12) secured to the second part of the case which is suitably guided upon closure by the guide plate 15 attached to it.

The operation is as follows:

When the case is closed the stop plate 14 abuts upon the bolt 10 which yields, compressing the spring 13 and falls back over the plate 14 when the two parts of the case are brought together.

When the case is carried by the handle the pin 5 occupies the position shown in Figure 1, at the top of the slot 4, the effect of which is to strongly maintain the closure.

Finally, when it is desired to open the case it is sufficient to exert a simple pressure upon the end of the handle 8 which is connected to the pin 5. The effect of this is to release the bolt 10 from the plate 14 and the case opens.

The device described above only forms one example of the application of the invention. It will in fact be seen that its constituent members may be arranged in any other way without on that account going outside the scope of the invention. For example the bolt lever may be single or double, the spring may be of any shape, the latch plates and guides integral or otherwise. Finally the frame and the various parts may be made of any suitable material, stamped out or machined in any desired manner without going outside the scope of the invention.

What I claim is:

1. A closing device for hand baggage, cases, and the like comprising a casing adapted to be secured to one side of the receptacle to be closed, and a latch plate secured to the other side, a bolt lever pivotally mounted intermediate its ends within said casing, having a bolt portion at one end

offset laterally of the plane of oscillation of said lever and extending through an aperture in said casing, a spring within said casing normally pressing said bolt lever, 5 to project said bolt in position to engage said latch plate when the sides of said receptacle are brought together, said bolt being formed with a cam side, adapted to ride over said latch plate and snap behind it under the 10 pressure of said spring, a handle for said receptacle having an end thereof pivotally connected to the opposite side of said lever for assisting said spring to maintain said bolt in latched position when said handle 15 is grasped, said bolt being released by pressure of said end of said handle toward said receptacle.

2. A closing device for hand baggage, cases, and the like, comprising a casing 20 adapted to be secured to one side of the receptacle to be closed, and a latch plate secured to the other side, a bolt lever pivotally mounted intermediate its ends within said casing, having a bolt portion at one

end offset laterally of its plane of oscillation 25 and extending through an aperture in said casing, a spring within said casing normally pressing said bolt lever to project said bolt into position to engage said latch plate when the sides of said receptacle are brought together, said bolt being formed with a cam side adapted to ride over said latch plate and snap behind the same under pressure of said spring, a handle for said receptacle having an end thereof pivotally connected to the opposite end of said lever, outside said casing, said pivotal connection extending through an elongated slot in the side of said casing, said pivotal connection being movable within said slot to oscillate said lever, 30 to reinforce the latching pressure of said spring when said handle is grasped, said bolt being released by pressure of said handle toward said receptacle.

In testimony whereof I have signed my 45 name to this specification.

HIPPOLYTE ROMANOFF.
